SPARKLER TOY

Filed Aug. 20, 1929

Inventor

JOHN E. MALKIN.

By *Clarence O'Brien*
Attorney

UNITED STATES PATENT OFFICE

JOHN E. MALKIN, OF NEW YORK, N. Y.

SPARKLER TOY

Application filed August 20, 1929. Serial No. 387,255.

This invention relates to toys and has for its primary object, the provision of a spark producing toy for children.

Another object of the invention resides in a toy sparkler which produces a cold spark not to be dangerous or harmful should the same come in contact with the hand or body of a child and which produces a stream of light which will be amusing to the child in view 10 of the fact that it is produced by the manual operation of the child.

Another object is to provide a toy sparkler which includes a rotatable flint wheel against which a steel block is held under tension, and 15 a gear train operable by the manual turning of a crank which is operatively connected to the flint wheel for imparting rotation thereto by which sparks are produced due to contact of the wheel with the friction surface of the 20 steel block.

A further object is the provision of a child's sparkling toy which is simple of construction, inexpensive of manufacture, and easy of operation.

25 With these and other objects in view, the invention resides in a certain novel construction, combination and arrangement of parts, the essential features of which are herein-after fully described and are particularly 30 pointed out in the appended claim, and illustrated in the accompanying drawing, in which:—

Figure 1, is a side elevational view of my improved toy sparkler.

25 Figure 2 is an end elevation thereof.

Figure 3 is a detailed perspective view of the friction block, and the spring holder therefor.

Referring particularly to the drawings, the 40 reference character 10 designates my improved sparkler toy in its entirety which includes a frame or handle member 11 constructed of metal and which is provided at one end with a handle portion 12, while the

45 opposite end is bifurcated or forked to provide spaced parallel arms 13—13. Journalled in the terminal ends of the arms 13—13 is a shaft 14 on which a flint wheel 15 is fixedly mounted together with a gear 16 so that both

50 the wheel 15 and gear 16 rotate as a single

unit. One of the arms 13 has its terminal end slightly offset as at 17 to facilitate of the mounting of the gear 16 and wheel 15 side by side as shown in Figure 2 of the drawing.

Also journalled in the arm 13 adjacent the 55 handle portion 12 is a crank shaft 18 to which a relatively large drive gear 19 is fixedly mounted, while the outer end of the crank carries a manipulating knob 20 by which manual rotation may be imparted to 60 the gear 19 for a purpose to be presently appreciated. Journalled in the arm 13 intermediate the crank 18 and shaft 14 is a shaft 21 which carries a relatively large gear 22 to one side of which is connected a smaller 65 gear 23, the latter constantly meshing with the drive gear 19, while the former gear 22 meshes with the gear 16. From the foregoing it will be seen that I have provided a gear train between the crank shaft 18 and the 70 shaft 14 on which the flint wheel 15 is mounted whereby upon rotation of the crank, power will be transmitted to the shaft 14 through the intermeshing gears as hereinbefore described.

75 Fixed to one of the arms 13 as at 24 is a friction block holder in the nature of a resilient spring arm 25 constructed of flat springy metal, the upper free end of which is provided with a head 26 for receiving the 80 rectangular shape friction block 27 which may be of steel or other like metal. The block 27 is provided with a roughened concave surface 28, the curvature of which approximates the curvature of the periphery 85 of the wheel 15 and in practice the spring arm 25 tends to hold the friction surface of the block 27 against the periphery of the wheel 15. The head 26 is provided with side arms or ears 29 which act to prevent lateral 90 shifting of the friction block 27 relative to the head. The block 27 is also removable from the head 26 to facilitate of the insertion of a new one when desired.

In operation, the toy is held by one hand 95 of the child or operator while the manipulating knob 20 of the crank is grasped by the other hand whereupon the operator proceeds to impart turning movement to the crank 18 from where power is transmitted to the gear- 100

ing to the rotatable flint wheel 15. As the periphery of the wheel passes the friction surface 28 of the friction block 27, a continuous shower of sparks will be produced which imparts the appearance of a stream of light. The sparks produced by the device may be turned "cold" and are harmless should they come in contact with the skin or clothing of the operator, thus there is no possibility of injury due to burning of the operator's hands or clothing.

Having thus described my invention, what I claim as new, and desire to secure by Letters-Patent, is:

15 A sparkler toy of the character described comprising a handle member, a pair of spaced, opposed, parallel arms extending longitudinally from one end thereof, a train of meshed gears mounted for rotation at longitudinally spaced points between the arms, a
20 steel friction wheel fixed for rotation to the gear remote from the handle, an actuating crank operatively connected to the gear adjacent the handle, a resilient arm secured to one of the first named arms and extending substantially parallel therewith in spaced relation thereto and terminating adjacent the periphery of the friction wheel, integral ears on the free end portion of the resilient arm
25 extending inwardly over opposite sides of the friction wheel and a friction block removably mounted on the resilient arm between the ears and having a concaved face disposed in yielding engagement with the periphery of the friction wheel.

30 35 In testimony whereof I affix my signature.
JOHN E. MALKIN.
